UNITED STATES PATENT OFFICE.

ARTHUR R. MISKIN, OF UCON, IDAHO.

ROAD SCRAPER.

Application filed June 26, 1925. Serial No. 39,773.

My invention relates to road scrapers in which are employed blades for scraping and smoothing road beds or other earth surfaces over which they may be dragged, the blades 5 usually being of metal and set vertically, or nearly so, and arranged diagonally to the course of the scraper, as in operation it is moved over the ground. It has heretofore usually been the practice to construct the 10 scraping bars or blades of apparatus of the kind referred to, of wooden bars, reinforced with metal to form cutting or scraping edges that may be easily maintained sharp and of the desired outline. However, there 15 are objections incident to this form of road scraper, such as excessive weight, cumbrousness, cost of manufacture, and tendency to clog in operation due to cumbersome construction.

20 My invention consists in a road scraper formed of metal bars supported vertically so as to present to the surface to be operated upon cutting or scraping edges, the bars being united to each other in a novel 25 manner, as will be described, to produce a very rigid frame.

In the drawings,

Figure 1 is a perspective view of a road scraper made according to my invention. 30 Figure 2 is a rear elevation of the device. In the drawings, 2, 2' indicate the longitudinal bars of the apparatus. These, like the other bars that constitute the blades of the scraper and which will presently be 35 described, are formed of steel, stock material of 6 inches in width, and $\frac{3}{8}$ of an inch in thickness, being well suited for an ordinary road scraper. These side bars are united at their forward ends by a cross connecting piece 3, which may be of wood, so 40 as to constitute a sort of platform for the operator. Upon this cross piece is supported the driver's seat 4. Between and uniting the longitudinal side bars are the diagonally disposed scraper blades, which are 45 arranged in two sets, oppositely inclined, and crossing each other at approximately right angles. One set of parallel scraper blades is formed of the diagonal bars 6, and 50 6', 27. While there are but two blades in this set, a greater number might be used if a scraper larger or longer than that shown should be made. The other set of parallel diagonal scraper blades is formed of the 55 bars 7, 7', and 8; the blades of the two sets crossing each other intermediate the longi-

tudinal side bars and being united at their intersections. The diagonal bar 6 is secured at its front end to the side bar 2', preferably beneath the connecting piece 3, whence 60 it extends rearwardly entirely across the scraper to the opposite side where it is united, at 13, to the rear diagonal bar 8. The bar 6 is disposed vertically throughout the greater portion of its length, so that 65 its lower edge serves as a scraping or cutting blade to act on the road or other surface over which the apparatus may be dragged. Toward its rear end it is twisted, as at 11, to produce a horizontal portion, 70 12, that extends across the upper edge of the diagonal bar 8 close to its attachment to the side bar 2. The rear end of the bar 6 is bent downward, as at 13, so it may lie close against the rear face of the bar 8 to 75 which it is secured fast, as by rivets. The diagonal bar 6', which approximately parallels the rear half of the bar 6, is attached, at 10', to the longitudinal bar 2' at about 80 its middle. It is throughout its main portion vertically disposed, and is formed near its rear end with a twist 11', a horizontal part 12' that crosses the upper edge of the bar 8 at about its middle part, and a downwardly bent end 13' that is secured fast to 85 the rear face of the bar 8. The diagonal blade, formed in part by the bar 6', is continued, in its general direction, by the bar 27, which is attached at 28 to the rear diagonal bar 8 and extends thence to the rear 90 end of the longitudinal bar 2, to which it is secured at 21. The bar 27 is slightly twisted so that the lower edge of its rear portion 23 lies in a plane higher than that 95 occupied by the edge of the forward part of the bar 27, leaving an open space 25 below the rear portion of this rear diagonal bar, for a purpose to be described. The longitudinal bar 2 is twisted near its rear end 100 at 19 so that there is formed an elevated horizontal portion 20 that crosses the upper edge of the diagonal bar 27 near its rear end, and the end of the bar 2 is turned downward at 21 and riveted or otherwise securely united to said bar 27. The front 105 diagonal blade of the other set crosses the blade 6 at about right angles, and is, for construction purposes, formed of two parts, 7, 7'. The former is riveted or otherwise secured to the longitudinal bar 2, preferably beneath the cross piece 3 and directly 110 opposite the connection of the bar 6 with

the longitudinal bar 2'. Near its rear end and adjacent to the bar 6, the bar 7 is twisted, at 16, so that there is formed a horizontal portion, 17, adapted to cross over the diagonal bar 6 near its middle. The end of the bar 7 is down-turned and is riveted or otherwise secured to the bar 6, at 18. The second portion, 7', of this diagonal blade is secured, at 15, to the diagonal bar 6, is twisted at 16' to form the horizontal portion 17', and is secured, at 18', to the diagonal blade 6' adjacent to its connection with the side bar 2'. The rear diagonal blade 8 is secured at its forward end, at 26, to the longitudinal bar 2, is secured at its middle to the diagonal blade formed of the bars 6' and 27, and at its rear end is secured, at 21', to the rear end of the longitudinal bar 2'. The latter is twisted at 19' so as to form the horizontal part, 20', that extends over the upper edge of the rear diagonal blade 8. The blade 8 is bent or twisted so that the lower edge of its rear portion 22 occupies a position above the general cutting plane of the scraper, there being thus left an open space 25 below this elevated lower edge of the rear part of the blade 8.

It will be seen from the foregoing description that the scraper is formed with oppositely inclined diagonal blades rigidly united with each other at their intersecting points, and at their ends secured to the longitudinal side bars, thus producing a very rigid and well braced frame. The intersecting scraping blades produce a series of spaces enclosed by the blades, the central space,—between the blades 6, 6' and 7', 8,—being four-sided, and the others triangular. It will also be seen that there is formed at the rearmost corner of each of the enclosed spaces an opening 24, below the horizontal portion of one of the diagonal blades bounding such enclosed space, and adjacent to an oppositely inclined diagonal blade bounding another space. These openings permit the earth and the material that may be removed from the surface of the ground by the scraping blades, which does not lodge in the depressions of the surface over which the scraper is being dragged, but is moved by the diagonal blades towards the openings 24, to pass through the same into the next enclosed space, to be there caught by a diagonal blade bounding that space and carried across the surface being operated upon to fill the depressions therein. The earth loosened by the scraper is thus moved backward and forward across the path covered by the scraper, passing from one enclosed space to the next in rear, with the result that the surface left by the passage of the scraper is smoothed and well dressed, the raised portions being cut off by the blades, and the depressions being filled with the material loosened by the scraper blades and shifted back and forth as

described, by the passage of the apparatus. The diagonal blades that bound the rearmost enclosed spaces of the scraper are, as has been described, inclined so as to leave open spaces 25 beneath their lower edges towards the sides of the apparatus. The purpose of this arrangement is to permit the finer material that has been moved by the scraper and collected in the said rearmost spaces, to be spread over the surface being smoothed, instead of being delivered through the openings 24 in ridges at the sides of the path of the apparatus, as is customary with scrapers of this kind. Some of the material finally delivered at the rear of the scraper will be of such size as to preclude its passing through the spaces 25 beneath the rearmost diagonal blades, and this passes through the openings 24.

The scraper is provided with any suitable draught attachment, as indicated at 5, which may be secured to metal brace pieces 9 secured to the underside of the front connecting piece 3, and at their rear ends to the diagonal blades 6 and 7.

A scraper such as described is very stiff and rigid in its construction; weighs much less than a wooden scraper reinforced with metal scraping blades, and yet has sufficient weight for practical purposes; is less cumbersome than a wooden scraper, and operates more satisfactorily, because the material moved by the cutting blades cannot lodge under the blades and be dragged by the scraper, as occurs when relatively wide wooden bars are employed to constitute the frame of the apparatus.

I wish it to be understood that my invention is not limited in its useful applications to the particular structure shown, since the number of bars, and the size of parts, may be varied from what is shown, and some of the features might be used in a metal-reinforced wooden frame scraper. Therefore, the invention is not to be limited beyond what is expressed in the claims hereof.

What I claim is:

1. A road scraper, comprising diagonal blades arranged in oppositely inclined sets which cross each other; the blades being rigidly secured to each other at their intersections and at their ends secured to side frame pieces of the scraper.

2. A road scraper, comprising diagonal blades arranged in oppositely inclined sets which cross each other; thus forming spaces enclosed by the blades, there being openings from the rear portion of one enclosed space into an adjacent space located toward the rear, whereby the earth material moved by the blades is caused to pass across the surface being acted upon and subjected to the action of the blades to fill depressions.

3. A road scraper, comprising longitudinal side bars and diagonal scraping blades

- between the side bars, such blades being arranged in two sets that cross each other, the blades being rigidly connected to each other at their intersections and at their ends secured to the side bars, the intersecting blades forming enclosed spaces, and there being openings in the rearmost corner of each space for the passage of material moved by the scraper blades.
- 10 4. A road scraper, comprising side longitudinal bars and diagonal scraper blades formed of metal supported on edge, the blades being arranged in two oppositely inclined sets that cross each other and united at their places of intersection, certain of the blades being shaped adjacent to their intersections to have horizontal parts under which are spaces through which material moved by the blades may pass.
- 15 5. A scraper, comprising longitudinal side bars and diagonal scraper blades, oppositely inclined and crossing each other, the rear ends of the rearmost scraper blades being rigidly secured to and supported by the rear ends of the longitudinal bars, and the latter being formed with horizontal portions that are raised above the cutting plane of the scraper, whereby are formed spaces through which material moved by the blades may be delivered at the sides of the scraper.
- 20 6. A scraper, comprising longitudinal side bars, and diagonal scraper blades, oppositely inclined and crossing each other, the rear ends of the rearmost scraper blades being rigidly secured to and supported by the rear ends of the longitudinal bars, and the lower edges of the rear end portions of said blades being elevated above the cutting plane of the scraper to permit fine material to pass under the same and be spread by the scraper, the rear ends of the longitudinal bars adjacent to their connections with the scraper blades being constructed to form spaces through which coarse material moved by the blades may be delivered at the sides of the scraper.
- 25 7. A road scraper, comprising a pair of longitudinal side bars, disposed vertically, their rear ends being twisted to form raised horizontal portions, a pair of diagonal cutting blades formed of metal bars set vertically, another pair of oppositely inclined diagonal cutting blades formed of metal bars set vertically, the oppositely inclined blades intersecting each other and being rigidly united at their intersections, and one blade at each intersection being twisted to form a horizontal part that overlies the blade it intersects, and the rear ends of the rearmost blades being united with the raised horizontal rear portions of the longitudinal bars, there being spaces enclosed by the side bars and the blades, which spaces are connected by openings beneath the said raised horizontal portions of the blades.

ARTHUR R. MISKIN.
